UNITED STATES PATENT OFFICE.

BENJAMIN H. DIETZ AND ALBERT E. HANSEN, OF CHICAGO, ILLINOIS.

PHONOGRAPH.

Application filed May 21, 1921. Serial No. 471,384.

To all whom it may concern:

Be it known that we, BENJAMIN H. DIETZ and ALBERT E. HANSEN, citizens of the United States, and residents of Chicago, county of Cook, and State of Illinois, have invented certain new and useful Improvements in Phonographs; and we do hereby declare that the following is a full, clear, and exact description thereof, reference being had to the accompanying drawings, and to the letters of reference marked thereon, which form a part of this specification.

This invention relates to improvements in phonographs and consists of the matters hereinafter described and more particularly pointed out in the appended claims.

The object of the invention is to provide a novel and improved phonograph having a casing which is a reproduction in miniature of a piano, and which simulates a piano as to all its features and parts visible from the outside, said parts being combined and correlated in such manner that all of the functions and adjustments of the device as a phonograph are performed and made possible, without detracting from its appearance as that of a miniature piano.

In the drawings:—

Figure 1 is a perspective view of a phonograph embodying our invention.

Figure 2 is a top plan view thereof.

Figure 3 is a vertical detail section on an enlarged scale through the phonograph in a plane indicated by the line 3—3 of Figure 2.

Figure 4 is another vertical detail section through the phonograph in a plane indicated by the line 4—4 of Figure 2.

Figure 5 is a detail perspective view of a fragment of a dummy keyboard embodied in the casing of the phonograph.

The invention as herein illustrated is embodied in a casing simulating the "grand piano" type of casing, but as will be apparent, other types of piano casings, "upright" or the "square" piano casings may also be used without departing from the spirit of the invention.

Referring now to the accompanying drawings:—10 indicates a casing which is that of a "grand piano" in miniature. The casing

is substantially shallow, horizontally, is three-cornered kind, and is mounted upon upright supporting legs 11. It has an upright front wall 12 and upright left and right-hand side walls 13 extending at right angles to the front wall. The side walls are reversely curved and merge into each other at the rear, as is usual in grand piano casings. Included in the casing is a horizontal bottom wall 14 (see Figure 3) which projects forwardly of the plane of the front wall 12 to provide a keyboard space 15,—the forward ends of the side walls 13 being extended beyond the front wall and being finished off to meet the projecting part of the bottom wall to carry out the desired appearance. The front wall 12 has its bottom edge spaced above the bottom wall 14, as shown in Figure 3, and fixed to the front and side walls is a second horizontal wall or motor board 16, which is located a suitable distance above the bottom wall to provide a space 17 that opens into or communicates with the key-board space 15 at the front of the casing. 18 indicates the usual two part lid 75 which is hinged along one edge to the left-hand side wall 13,—there being a prop or brace 19 hinged to the motor board to hold the lid in its open position.

Projecting forwardly from the front wall 12, near its bottom edge is a fall-board platform 20, which overhangs a part of the key-board space 15. To the inner faces of the front extensions of the side walls 13 of the casing, between the bottom wall 14 and the fall-board platform 20, are fixed horizontal cleats 21, upon which rest the ends of a dummy keyboard 22. The rear edge of said keyboard engages that part of the front wall 12 which extends below the fall-board platform (see Fig. 3). This dummy keyboard is made of a block of wood cut and finished to represent the black and white keys 22^a, 22^b respectively, of a piano keyboard (see Fig. 5). In said keyboard are provided a plurality of openings 23 which communicate with the space 15 beneath the keyboard. Preferably these openings are at the rear of the keyboard and open through the sides of the black keys 22^b. Thus these openings, 100

which provide one set of sound wave outlets through the keyboard space 15, are rendered substantially invisible to an observer.

Below and in front of the dummy keyboard, and resting upon the bottom wall 14, is an edgewise arranged removably fixed grill work bar or keyboard rail 24, in which are provided grill openings 24^a that communicate with the keyboard space 15 and provide a second set of sound wave outlets for said keyboard space. Secured to the rear face of the grill bar is a strip of textile material such as silk which hides the interior of the keyboard space from view. The grill bar is normally concealed by a drop board 26 which is hinged at its bottom edge to the front marginal part of the bottom wall 14 of the casing. When this drop board is down in the position shown in Figure 1, the grill openings in the bar or rail 23 are uncovered and sound waves may pass from the space 15 out through said openings.

To the front edge of the platform 20 is hinged a fall-board 27, which is of L-shaped cross section. When the fall-board is in the closed position shown in Figure 3, it covers the keyboard, and rests with its free edge upon the drop board 26, and when it is in its open position as shown in Figure 1, it rests upon the top surface of the platform and permits the sound waves to issue freely through the keyboard openings 23.

It is apparent from the foregoing description that a representation of the keyboard and adjacent parts of a grand piano casing is produced, which is so constructed as to provide sound openings that are practically invisible so that the appearance of a real piano keyboard is maintained. The drop board and the fall-board not only act to carry out the general appearance and effect of a piano, but they also function as means to modify or damp the sound waves issuing through said openings.

Above the horizontal wall or motor board 16 of the casing, is located the sound reproducing mechanism of the phonograph. It comprises a horizontally disposed turn table 30, mounted on the top end of an upright shaft 31, the bottom end of which extends through said motor board and into the space 17 where it is operatively connected to the driving motor (not shown) secured to the underside of said motor board. To the rear and to the left of the turn table shaft as shown in Fig. 2, is a tone arm base flange 32. This base flange supports in the usual manner, one end of a tone arm 33, the other end of which carries a stylus holding sound reproducer 34. In the space between the bottom wall and motor board of the casing is a sound amplifying horn or chamber 35 which communicates at its smaller end with the tone arm 33, and at its larger end, with the space 15 beneath the dummy key-

board. The keyboard end of this chamber is of a height approximating the spacing between the bottom wall and motor board wall, and is of a width equal to the spacing between the side walls 13 of the casing at its keyboard side.

In the casing toward the rear, between the bottom wall and motor board, is provided a plurality of compartments 36 which open through the motor board to receive and hold the records to be played. Preferably we provide in said compartments a plurality of indexed division cards 37 secured in any suitable manner, which cards make it possible to arrange the records in indexed order for the purpose of selection.

When a record has been placed upon the turn table and played, the sound waves pass through the tone arm 33 into the smaller end of the sound chamber 35, to be amplified therein on the way to the outlet openings in the dummy keyboard and grill bar or rail. Should it be desired to modify or damp the sound waves, either the drop board 26 or the fall-board 27 may be closed to attain the desired volume of tone or both may be closed at the same time for further modification.

While in describing our invention we have referred to certain details in construction and arrangement of parts, we do not wish to be limited thereto except as may be pointed out in the appended claims.

We claim as our invention:

1. A phonograph, comprising a piano-like casing having a dummy keyboard provided with openings therein, a sound reproducing mechanism in the casing spaced from the keyboard, and means providing a sound chamber leading from the sound reproducing mechanism and terminating at the keyboard.

2. A phonograph comprising a piano-like casing having a dummy keyboard provided with openings therein and a fall-board hinged to the casing above the keyboard, a sound reproducing mechanism in the casing spaced from the keyboard, and means providing a sound chamber leading from the sound reproducing mechanism and terminating at the keyboard, the openings in which provide an outlet for the sound chamber, the said fall-board being adapted to be swung into a position to enclose the keyboard so as to modify the sound waves issuing through the openings therein.

3. A phonograph comprising a piano-like casing having a dummy keyboard and a keyboard rail below the keyboard, said keyboard and rail being provided with openings, a sound reproducing mechanism in the casing located back of the keyboard, means providing a sound chamber leading from the sound reproducing means and terminating at its front end at the keyboard and rail, the

openings in which provide outlets for the sound chamber, a fall-board hinged to the casing above the keyboard, and a drop-board hinged to the casing along the bottom edges of the keyboard rail, said boards being adapted to be swung toward said keyboard and said rail openings to modify the sound waves issuing therefrom.

5 In testimony that we claim the foregoing

as our invention, we affix our signatures in 10
the presence of two witnesses, this 18th day
of May, A. D. 1921.
